(57) CLAIM

The ornamental design for a receiver mounted umbrella stand and tray, as shown and described.

DESCRIPTION

FIG. 1 is a perspective view of the receiver mounted umbrella stand and tray with an umbrella and a fragmentarily shown truck shown in dashed lines.

FIG. 2 is a front view of the present invention;

FIG. 3 is a rear view of the present invention;

FIG. 4 is a right side view of the present invention;

FIG. 5 is a left side view of the present invention;

FIG. 6 is a top view of the present invention; and,

FIG. 7 is a bottom view of the present invention.

The broken line showing of environment is for illustrative purposes only and forms no part of the claimed design.
